DESIGN FOR A HEEL

Mannie Coen, New York, N. Y.

Application February 2, 1940, Serial No. 89,945

Term of patent 3½ years

To all whom it may concern:

Be it known that I, Mannie Coen, a citizen of the United States of America, residing in New York city, in the Borough of Manhattan, county and State of New York, have invented a new, original, and ornamental Design for a Heel, of which the following is a specification, reference being had to the accompanying drawing, forming part thereof, wherein:

I claim:

The ornamental design for a heel, substantially as shown.

MANNIE COEN.
